SICKLE BAR SHARPENING IMPLEMENT

Lester T. Ferrin, Tonasket, Wash.

Application April 14, 1951, Serial No. 221,080

3 Claims. (Cl. 51—36)

1

My present invention relates to tools and more particularly to a sickle bar sharpening implement.

One object of the invention lies in the provision of a frame which is adapted to receive and clamp in position for sharpening, a sickle bar of the common well known design.

Another object of the invention lies in the provision of a carriage movable longitudinally upon the frame and which carries an electric motor and grinding wheel for successively sharpening each tooth of a sickle bar.

Another object of the invention lies in the provision of the carriage with spaced track rollers united by means of an underslung U-shaped frame which supports transversely extending spaced guides adapted to slidably support a base or mounting plate upon which the motor and grinding wheel are suitably mounted and operably connected together.

Another object of the invention lies in the provision of an implement of this type which is simple to manufacture and may be produced with facility at a low cost and which is very useful and capable of performing the function of sickle bar sharpening.

Other objects will be apparent during the course of the following description.

In the drawings, forming a part of this application, and in which like numerals are employed to designate like parts,

Figure 1 is a perspective view of my improved sickle bar sharpening implement with one leg broken away for convenience of illustration.

Figure 2 is a transverse cross section taken through the implement central of the carriage and with the motor shown in elevation.

Figure 3 is a plan view of the carriage and fragments of the track and a parallel sickle bar, and,

Figure 4 is a perspective view of the U-shaped frame having its spaced transversely disposed guides secured thereto and with the track rollers removed.

Referring now more particularly to the drawing, I have shown in Figure 1 a frame comprising inverted U-shaped angle iron end portions 5 and 6 each of which has downwardly disposed outwardly spread legs 7 united at their top ends by a horizontal section 8 of the angle iron from which the legs are formed. The angle iron is positioned with flange 9 arranged to dispose a flat face 9' outwardly and a flange 10 is thus disposed inwardly. Suitable braces 11 are secured as by rivets, or other suitable means, to the flanges 10

2

of the legs 7 substantially midway their length and angle upwardly to a point midway the length of a companion horizontal section 8 and are there secured in overlapping position by means of a single rivet or bolt.

A longitudinally extending clamping bar 12 is formed of angle iron and is secured at each end to a horizontal section 8 adjacent the front leg 7 of spaced end portions 5 and 6. The clamping bar 12 is positioned with its depending flange 13 on the inner edge and its lip extending forwardly therefrom and disposed in a horizontal plane. This necessitates its being secured in face to face relation with the under side of flange 9.

Angle braces 12' are secured between the clamping bar flange 13 and the front leg flanges 9 to lend rigidity to the clamping bar and support the front legs against longitudinal pressure on the frame.

Rearwardly spaced from clamping bar 12 and in parallel relation thereto I have provided a tubular track 14 secured upon the upper face 9' of horizontal section 8 of each end portion 5 and 6 by means of bolts and the track 14 is forwardly spaced from the juncture of rear legs 7 and their companion horizontal sections 8, to maintain the motor and carriage weight within the vertical plane of the lower end of the two rear legs 7 and preclude unduly spreading the legs 7.

Spaced track rollers 15 are provided with concave faces adapted to conform to the tubular track 14, and these track rollers are bearinged on stub shafts 16 supported in inwardly disposed aligned bosses 17 carried by upwardly extending ears 18 which are a part of and extend from the U-shaped body 19 of the carriage frame 20.

Transversely extending spaced parallel angle bars form guides 21 with their horizontal supporting lips 22 disposed in inwardly opposed relation and with their vertical flanges 23 extending upwardly at the outer edge of said lips. These guides thus permit transverse sliding movement of mounting plate 24, but confine the longitudinal movement with relation to the carriage frame. Longitudinal movement of the carriage is permitted when desired by movement of the rollers along track 14.

Secured on the mounting plate 24 of the carriage, I have provided an electric motor 25 suitably switched at 26 in the power supply cord 27. A belt pulley 28 is provided on the motor shaft and a belt 29 is trained about said pulley and also about a second pulley 30 mounted on grinder shaft 31 rotatably mounted in spaced self align-

ing bearings 32 secured adjacent the forward end and on the under side of mounting plate 24.

Angle-faced grinding wheel 33 is secured on the end of shaft 31 opposed to pulley 30 and is positioned spaced from the side edge of mounting plate 24 to facilitate sharpening a sickle bar.

For ease in manipulating the sickle bar sharpening implement, I have provided the mounting plate 24 with a forwardly extending handle 34 secured thereto as by welding.

The sickle bar 35 is placed upon the clamping bar 12 with the teeth to be sharpened extending inwardly and their beveled edges upwardly disposed and clevis clamps 36 are then positioned to clamp the sickle bar to the clamping bar flange lip 13'.

With the motor driving the angle-faced grinding wheel, the carriage is moved by grasping the handle and raising the grinder above the level of the sickle bar. The mounting plate 24 is then slid forward in the guides 21 to position the grinder wheel directly above the teeth to be sharpened. The carriage is then permitted to tilt downwardly in front until the grinding wheel contacts the teeth and upon contact the mounting plate is slid rearwardly causing the wheel to sharpen the full bevel surface of the two adjoining edges of adjacent teeth. The carriage is then moved longitudinally on the frame to position the grinding wheel above the next successive adjoining teeth for repeating the same sharpening operation.

Having thus described my invention what I claim as new and desire to secure by Letters Patent is:

1. A manually controlled sickle bar sharpening implement comprising a supporting frame having end portions; downwardly spread front and rear supporting legs on the end portions; a horizontal section uniting the upper ends of companion legs; a clamping bar having a lip disposed in a horizontal plane extending between said end portions and secured to said horizontal sections adjacent said front legs; a tubular track secured to said horizontal sections in spaced parallel relation to said clamping bar; a longitudinally movable frame; concave track rollers on said track and supporting said movable frame; transversely positioned spaced guides on the movable frame; a mounting plate having a handle and reciprocably mounted in said guides for transverse movement with relation to said movable frame; said moveable frame and mounting plate being vertically tilttable with relation to said supporting frame; a motor mounted on said

mounting plate; an angle-faced grinding wheel rotatably mounted on the under side of said mounting plate; belt means for transmitting rotary motion from the motor to the grinding wheel; and clevis clamps for clamping a sickle bar in a horizontal plane to said clamping bar, whereby a sickle bar may be positioned for sharpening by said grinding wheel.

2. In a sickle bar sharpening implement having a supporting frame and a reciprocable mounting plate carrying a rotatable grinding wheel, a carriage moveable longitudinally on the frame and adapted to support said mounting plate comprising a U-shaped body adapted to encircle a portion of the frame, spaced rollers carried by said body and disposed to roll on a part of said supporting frame, and spaced guides rigidly secured on said body transversely of the direction of movement and adapted to slidably support said mounting plate.

3. A manually controlled sickle bar sharpening implement comprising a frame supporting tubular track, means carried by the frame for releasably securing a sickle bar in a horizontal plane and in spaced parallel relation to said track, a frame longitudinally movable on the track and secured against transverse movement thereon, transversely disposed guides on the movable frame, a mounting plate reciprocably mounted in said guides, said movable frame and mounting plate being vertically tilttable, a grinding wheel rotatably mounted on said mounting plate, means for rotating said grinding wheel, and a manually operated handle on said plate whereby the grinding wheel may be successively positioned to sharpen the teeth of a sickle bar.

LESTER T. FERRIN.
